UNITED STATES PATENT OFFICE

HARRY T. OGDERS, OF COLUMBUS, OHIO, ASSIGNOR TO THE COLUMBUS PHARMACAL COMPANY, OF COLUMBUS, OHIO, A CORPORATION OF OHIO.

ARTIFICIAL LEG.

No. 923,798.

Specification of Letters Patent.

Patented June 1, 1909.

Application filed August 3, 1908. Serial No. 446,519.

To all whom it may concern:

Be it known that I, HARRY T. OGDERS, a citizen of the United States, residing at Columbus, in the county of Franklin and State 5 of Ohio, have invented certain new and useful Improvements in Artificial Legs, of which the following is a specification.

My invention relates to improvements in artificial legs, and comprises a device for use 10 in connection with a leg formed with a pivot at the knee, so that the lower portion may be swung inwardly or outwardly as nearly as possible after the manner of the natural leg.

15 My improvement provides a device, whereby, through the forward or rearward movement of the shoulders of the wearer, the lower leg member may be swung forwardly or rearwardly as desired, and at the same 20 time the pivot at the knee may be made firm enough to prevent bending of the leg when it is not desired.

The construction of my device is shown in 25 the accompanying drawings which are hereto attached and hereby made a part of this specification, in which—

Figure 1 is a side view of the artificial leg with my device in place thereon; Fig. 2 is a front view; Fig. 3 is a rear view; Fig. 4 is a 30 detail of the swinging pulley on the lower leg member; Fig. 5 shows the leg in bent position.

Referring to the drawings in which the same numeral indicates the same part 35 throughout, 1 is the upper artificial leg member, having pivoted thereto at the knee 2 a lower leg member 3; on each side of the lower leg member at an appropriate point below the knee to produce the leverage desired, I 40 position roller constructions 4 and 5, each comprising preferably the plate 6 screwed or otherwise secured to the leg member at 7, and carrying the pin or pivot 8 thereon on which is mounted an arm 9, to swing freely 45 forwardly or rearwardly; this arm 9 carries the pulley 10 mounted at 11 to turn freely; preferably, the arm 9 is divided, and between the same and member 12 thereof the pulley 10 is placed, whereby is formed a 50 guide for the cord to confine the same to the said pulley. This construction enables the cord bearing roller or pulley to swing forwardly and rearwardly as may be demanded during the manipulation of the lower leg

member in a manner hereinafter described. 55 On the front of the upper leg member at a slight distance above the knee 2, are placed loop guides 13 and 13^a whereby the cord is arranged for manipulation of the lower leg member in its forward movement. On the 60 upper leg member preferably at the sides thereof, are placed rollers or guide pulleys in pairs 14 and 15; on each side there is mounted preferably a plate 16 upon which are mounted the pivoted rollers or guide pulleys 65 17, 18 to turn freely under the influence of the cord as hereinafter described. At the rear side of the upper leg member there are placed loop guides 19 and 19^a through which the cord is adapted to pass and to be held in 70 proper position.

A suspender 20 is provided, formed preferably of the side strips 21 and 22 to be fitted upon the shoulders of the wearer, and the cross strip 24, preferably at the back of the 75 wearer; at the ends of the side strips are provided hook or clasp members 25, 26, 27 and 28 to each of which is adapted to be secured an end of the cords 29 and 30. The cord 29 is connected at one end to the hook 26, and 80 passes downwardly through the loop guide 19^a and is then led between the rollers 17 and 18, as shown, and then forwardly around the roller 10 on the lower leg member, and thence is brought upwardly through the loop 85 guides 13 and 13^a on the front of the knee and thence is carried upwardly to the hook 25 on the suspender 20. In a similar manner the cord 30 is led through the pulleys and guide on the other side of the artificial leg 90 member.

The operation of the device is as follows: The suspender having been placed over the head of the wearer and fitted upon the shoulders, the cords which are preferably left in 95 place upon the leg when it is detached, are secured to the ends of the suspender member; assume that the wearer is seated and the leg is in extended position; to bring the lower leg member to bent position, it would be necessary only to move the shoulders and upper portion of the body upwardly and rearwardly thereby exerting a stress upwardly and rearwardly upon the cords, the friction of the cords over the rollers or guide pulleys being 100 sufficient to pull or swing the lower leg member upon the knee pivot in the direction desired. The wearer, by expanding or con-

tracting the chest and consequently elevating or depressing the shoulders, can readily engage the suspender or harness with the body and carry the same upwardly and forwardly 5 or rearwardly as desired, and it is the result of only slight practice to manipulate the cords as desired through the movement of the shoulders and upper body portion by the wearer.

10⁴⁶ By arranging the swinging pulley or roller on each side of the lower leg member, and passing the cord upwardly therefrom over the front of the knee, I provide for the use of an endless cord so arranged that it is readily 15 manipulated, and unfailingly draws the lower leg member to its lengthened or straightened position; also, by the provision of the pair of rollers on each side of the upper leg member, between which the rear portion of the cord is 20 passed, and by the further provision of the rear guide on the upper leg member, the retraction or bending of the lower leg member is rendered certain and easy. These results 25 are accomplished essentially by the provision of the swinging pulley on the lower leg member and the arranging of the cord thereon over the front of the knee.

It is understood that there is some difficulty in the manipulation of any artificial leg 30 construction, and my improvements render it possible for the wearer by the movement of the upper portion of the body to swing the leg either forwardly or rearwardly as desired, and to do it with such ease and celerity as not 35 to unduly attract the attention of a spectator or attendant.

In the drawings and in the description, I 40 have set forth a construction and arrangement of parts which accomplish the object in mind; however, I do not desire to confine

myself to the specific parts and the arrangement thereof thus disclosed.

What I claim is:

1. An artificial leg construction comprising upper and lower leg members pivoted together, pulleys positioned on the lower leg member at each side thereof, guide rollers positioned on the upper leg member at each side thereof, a guide member positioned on the front of the upper leg member, a suspender member, and a cord secured at one end to the rear side of said suspender member and led through said guide rollers and pulley members on one side of said leg members and secured at its other end to the front 55 side of said suspender member. 45

2. An artificial leg construction comprising an upper leg member, a lower leg member adapted to swing forwardly and rearwardly thereon, a plurality of guide rollers placed at 60 the sides of said upper leg member, a swinging pulley placed at each side of the lower leg member, a guide placed on the front side of the upper leg member, a second guide placed on the rear side of the upper leg member, a 65 suspender member adapted to be fitted upon the shoulders of the wearer, and a cord member secured at one end to the rear side of said suspender member and passing through said rear guide and between said guide rollers and around said pulley and upwardly over the knee through said front guide and secured at its other end to the front side or portion of said suspender member. 70

In testimony whereof I affix my signature 75 in the presence of two witnesses.

HARRY T. ODGERS.
